UNITED STATES PATENT OFFICE.

NOAH R. WHITE, OF DELTA, COLORADO.

MILK AND MAIL RECEPTACLE.

1,274,224.

Specification of Letters Patent. Patented July 30, 1918.

Application filed July 10, 1917. Serial No. 179,713.

To all whom it may concern:

Be it known that I, NOAH R. WHITE, a citizen of the United States, residing at Delta, in the county of Delta and State of Colorado, have invented certain new and useful Improvements in Milk and Mail Receptacles, of which the following is a specification.

This invention relates to an improvement 19 in milk and mail receptacles and it is a purpose of my invention to provide a receptacle which can be mounted to be outside of a dwelling, office, or other building or room, and which is provided with a lock operable 25 only from the inner side of the wall upon which the receptacle is mounted.

A further object resides in so constructing the parts that a receptacle or box and a locking mechanism of a standard size can 20 be manufactured and placed upon the market, and then when the parts are installed adjustment can be made to suit the device for the thickness of the wall on which the receptacle is fitted, and for other conditions.

25 A still further object is to so construct the parts that the cover of the receptacle will be held open when it is desired that the receptacle be left for placing of milk, mail, or other matter therein, and in so arranging the locking mechanism that as the door 30 is closed it will be positively locked, means however being provided so that in this closing of the door an alarm will be sounded to thus indicate to a person within the building 35 or room where the lock is located, that the door has been closed.

With the above and other objects in view, which will be in part described and in part understood from the specification, drawings, 40 and claims, my invention consists in certain novel features of construction and combinations of parts which will be hereinafter more fully set forth in the claims.

In the drawings:—

45 Figure 1 is a view in section through a wall showing the structure of my invention mounted in a position for use;

Fig. 2 is a view taken at substantially a right angle to the disclosure in Fig. 1;

50 Fig. 3 is a view with parts in section, showing the arrangement of the structure on the inner side of the wall upon which the parts are mounted;

Fig. 4 is a view in elevation of the receptacle and showing the covers of the parts thereof open; and,

Fig. 5 is a fragmentary detail view to better illustrate certain of the adjustment features.

The wall generally indicated by the reference numeral 1 is of any character, and in setting the device of my invention it is only necessary to provide the opening 2 for the locking rod and to form bores for reception of the fastenings 3, although even in this latter instance it will be understood that screws might be used rather than the fastening bolts 3; and thus, it will be seen that the device can be fitted for use upon brick, stone, frame, or other walls, without the necessity of the employment of skilled mechanics and without materially cutting into or mutilating the wall.

The main receiving receptacle 4, which in the present instance is disclosed as constituting the two compartments 5 and 6, one of which might be for the reception of milk bottles, packages or the like, and the other for use as a mail box, is made to be substantially continuous throughout its side and bottom walls, and at the top the front and side walls are cut away to provide the bevel, at the upper edge of which the doors 7 and 8 are hinged. The purpose in providing bevelled doors or doors setting at an angle is to preclude the possibility of water standing upon these covers or finding its way into the compartments of the receptacle, as when the covers are inclined water will readily drain off. If desired, the compartments might have a letter slot tube 9 provided thereon so that even though the cover is closed and locked, mail matter can be placed within this receptacle. As has been stated, the bolts 3, or other suitable fastenings are passed through the rear wall of the receptacle and then are fastened in or through the wall. The opening 2, which is substantially a slot formed horizontally through the wall, is somewhat below the upper line of the back of the receptacle, and thus when the receptacle is mounted in place, rain, snow, and the like cannot drive through this opening and on the other hand the atmospheric air will not readily find its way through the opening. A bracket member 10 is mounted on the lower side of the cover 7 adjacent the hinge connection thereof, and a similar bracket 11 is carried on the lower side of the cover or door 8, the structure of these brackets being better shown in Fig. 5. A plurality of openings 12 are provided through each of the

brackets and the extension bars 13 have opening 14 therethrough which will register with the openings 12 and will permit passage therethrough of a bolt 15, or other suitable pivot fastening. By securing the bolt or other fastening through the registering openings of the bar 13 and the bracket associated therewith, the bar is so positioned that the free end thereof will extend into the opening 2 in the walls. As has been stated, the present disclosure shows a two compartment receptacle, and it will of course be understood that one of the bars 13 will be provided for each of the brackets 10 and 11.

Locking bars 16 and 17 are provided with a plurality of spaced apart openings 18, and the bars 13 have correspondingly spaced openings 19 provided at the free ends thereof, the bolts 20 being provided to be fitted through registering openings of the bars 13 and of the lock bars 16 and 17 to thus connect these members to be substantially continuous, substantially as shown in Fig. 2. A base plate 21 is adapted to be fitted on the inner side of the wall 1, and might be held in place by means of the fastenings 3, where these fastenings are made to form a bolt extending entirely through the wall or screws or other fastenings might be used to mount the base plate in the proper position upon the inner side of the wall. This base plate is preferably made of sheet metal which is folded over at the upper edge of the base plate and then after being bent back to form a keeper 22, is extended out to provide a guide bracket 23 after which the end of the plate is brought inwardly and is connected as at 24, with the lower edge of the base plate 21. The folded over portion of the strip as hereinbefore just described is slotted through at 25 and 26, for the reception of the locking bars 16 and 17 which are thus mounted to be capable of sliding movement above the guide bracket portion 23. A bell 27, or other suitable alarm or signal means, is mounted within the confines of the part of the sheet metal member where the same is extended from the guide bracket 23 to the lower end of the base plate 21, and the operating lever 28 of this bell is disposed just slightly below the guide bracket 23, which latter is slotted through as shown at 29 and 30, substantially just beneath the locking bars 16 and 17. Spring fingers 31 are carried by the locking bars 16 and 17 and extend down through the slotted openings 29 and 30 of the bracket plate 23 so that as these bars are moved forwardly or are shoved through the slot 2 in the wall, the spring fingers will ride over the operating lever 28 of the bell 27, but as the bars 16 and 17 are again extended from the inner side of the wall, the spring fingers 31 will engage with the bell operating lever 28 and in consequence this lever will be shifted to 65 ring the bell.

Locking levers 32 and 33 are pivotally mounted within the keeper 22 formed by folding over the material of the base plate 21, and these locking levers have portions 70 thereof extended to be substantially above the slotted openings 25 and 26, the springs 34 and 35 being provided to normally exert resilient force against the locking lever to swing the ends thereof to be within the lines 75 of the slotted openings 25 and 26. A locking notch 36 is provided in each of the locking bars 16 and 17, and a notch 37 is formed in each of the locking bars adjacent the end thereof, these notches 36 and 37 being so positioned that as the bars are moved endwise through the slotted openings 25 and 26, the locking levers 32 and 33 will be urged by the springs 34 and 35 to engage in the notches. The locking levers 32 and 33 have 80 the finger pieces 38 and 39 provided thereon and thus when it is desired to swing these locking levers against the force exerted by the spring, this can be done by simply pressing down upon the finger pieces 38 and 39. 85

It will of course be understood that the rear wall of the receptacle has the slotted openings 40 for the passage of the extension bars 13, and when the device is to be mounted in a position for use, the receptacle will be 90 secured upon the outer side of the wall so that the openings 40 thereof register with the slot 2 provided through the wall, and the base plate 21 will be mounted on the inner side of the wall with the openings 25 and 26 in the keeper portion 22 thereof substantially horizontally aligned with the opening 40 of the back wall of the receptacle 4. The locking bars 16 and 17 and the extension bars 13 connected therewith by means of the 100 bolts 20 are so adjusted that they accommodate substantially the thickness of the wall, and then the bolt 15 is so passed through the openings 12 and 14 that when the locking levers 32 and 33 are engaged in the notches 105 36 of the bars 16 and 17, the doors or cover members 7 and 8 will be held closed, the purpose in providing the plurality of openings 12 and 14 being to accomplish minute 110 adjustments of the extension bars 13 upon the bracket members 10 and 11 so that the covers 7 and 8 will be brought down tightly against the walls of the receptacle 4, to thus positively guard against rain, snow, and the like driving in under the cover, and also 115 against the insertion of an instrument to be used in prying up the cover, and further, it will be appreciated that where desired flanges might be provided along the edges of the covers to give additional protection. 120 As has been stated, the bell 27 is carried by parts or formed in conjunction with the base plate 21. With the parts mounted as, 125

above set forth, when the covers or doors 7 and 8 are moved to closed position, the locking levers 32 and 33 will engage in the notches 36 of the locking bars 16 and 17, and consequently these bars will be positively held against movement through the slot 2 of the wall; however, when pressure is exerted upon the finger pieces 38 and 39, the locking levers will be swung to inoperative relations even against the pressure of the springs 31 and 35, and then by exerting pressure upon the inner ends of the locking bars 16 and 17, the same may be moved through the slot or opening 2 and the covers 5 and 8 will be raised to give access to the compartments of the receptacle. When the parts have been brought to this relation and the locking levers are again released, they will engage in the notches 37 and thus the covers will be held against being closed to casual movement or through their own gravity weight, however, when it is desired to close covers, it is only necessary to exert sufficient downward swinging force 10 thereagainst that the locking levers will be disengaged from the relatively shallow notches 37 and then the locking bars will be moved inwardly to such extent that the spring fingers 31 thereof will engage with the bell operating lever 28 to cause the alarm or signal to be sounded, following which the spring finger will ride over this operating lever and the locking bars will be moved to bring the notches 36 thereof to a 15 relation to be engaged by the locking levers, in which relation the parts are positively locked and secured. Due to the fact that the fingers 31 are made of the spring type, as the locking bars 16 and 17 are moved in one 20 direction, the spring fingers will have no effect upon the bell operating lever 28 but will ride freely thereover, while upon movement of the bars in the opposite direction the fingers will engage with and swing the bell operating lever to operate the bell and thus signal to occupants of the building or 25 room, that one or both of the covers or doors have been closed down.

From the foregoing it will be seen that I have provided a structure which adapts itself particularly for use by house-holders or others, and which provides a receptacle mounted to be accessible from outside of a building or room, and yet provided with locking means which will be positively locked and secured when a cover for the receptacle is closed, and which at the same time cannot be released or unlocked except by a person within the building or room, 30 and while I have herein shown and de-

scribed only one certain specific form and construction of the parts, and one particular manner of mounting the same, it will be understood that changes and variations might be resorted to, and hence I wish to be limited to only such points as may be set forth in the claims.

I claim:-

1. A milk and paper receptacle including a receiving receptacle to be mounted on the outer side of a wall having an opening formed transversely therethrough, said receiving receptacle having an opening through the rear wall thereof in line with the opening of the wall, a base plate mounted on the inner side of the wall bent to form a supporting bracket for the alarm, and provided with an opening lined up with the opening of the wall and that of the receiving receptacle, a cover for said receiving receptacle, a bracket carried by said cover, a locking lever carried by the base plate adjacent the opening thereof, a locking bar provided with a notch for reception of the locking lever slidably mounted through the opening of the base plate and having its end bent to support a spring finger adapted to operate said alarm, and an extension bar adjustably connected with said locking bar and connected with the bracket of the cover. 90

2. A milk and paper receptacle including a receiving receptacle to be mounted on the outer side of a wall having an opening formed transversely therethrough, said receiving receptacle having an opening through the rear wall thereof in line with the opening of the wall, a base plate mounted on the inner side of the wall and provided with an opening aligned with the opening of the wall and that of the receiving receptacle, a cover for said receiving receptacle, a bracket carried by said cover, a locking lever carried by the base plate adjacent the opening thereof, a locking bar slidably mounted through the opening of the base plate and provided with a notch for reception of the locking lever, an extension bar adjustably connected with said locking bar and connected with the bracket of the cover, an alarm bell mounted upon the base plate, 100 and a spring finger carried by said locking bar to operate said alarm bell to automatically announce the closing and locking of the cover. 105

In testimony whereof I affix my signature in presence of two witnesses.

NOAH R. WHITE.
